3,394,820 STORAGE AND DISPLAY RACK

Erven Laff, 337 S. Wetherly Drive, Beverly Hills, Calif. 90211, and Sol Teichman, 13512 Hatteras St., Van Nuys, Calif. 91401

Filed June 22, 1966, Ser. No. 559,574
4 Claims. (Cl. 211—175)

This invention relates to display and storage racks for clothing and the like in which hangers are supported at their opposite ends by spaced parallel rails, and more particularly to improvements in the form, arrangement and supporting means for such rails.

In the retail merchandising of clothing, and especially of men's and women's slacks and shorts, a number of frequently conflicting requirements are imposed on storage and display fixtures. With hundreds or sometimes thousands of garments on hand, the typical clothing store or clothing department in a department store is always sorely pressed for storage space. The storage fixture must permit the compact stacking or hanging of, large numbers of garments without damaging or soiling them. Anyone who has ever tried to examine or, worse yet, removed a pair of trousers from near the bottom of a stack of such garments stored on a countertop recognizes the desirability of having storage means which provide for handy removal of all of the items contained in it.

Likewise, the desirability of having the largest possible number of individual garments openly displayed has long been known. The display should permit the maximum visibility of the greatest number of garments.

It is essential that any storage facility having display characteristics permit the rapid taking of an inventory and refurbishing of stock which has been depleted. This in turn necessitates a construction which permits convenient access to all parts, of the storage device by the retailer's employees. And the device must simultaneously provide equally facile access to the customer who wishes to examine and remove one or more of the stored garments before deciding whether to make a purchase or not.

In all but the most spacious of stores and departments, space saving is of cardinal importance. Both floor space and wall space are normally at a premium. Accordingly, any storage and display rack should provide for the maximum utilization of the floor space and minimum use of wall space.

It goes without saying that any structure used for supporting the great weight of large numbers of garments must be sturdily constructed. Naturally, since it will be visible to customers and potential customers it must be at the same time attractive.

The modern trend in interior decorating of retail clothing stores and clothing departments is to attempt to change the appearance and decor from time to time. To permit such redecorating without the need for expensive remodeling, it is highly beneficial for the storage and display fixtures to be lightweight and fairly easily moveable. In this connection great advantage is to be gained by manufacturing the device in modular form, so that several units may be combined in a variety of overall configurations.

The achievement of all of the aforementioned design features, characteristics and benefits, as well as many others which will become apparent from a reading of the following specification and claims is the object of the subject invention.

Essentially the invention comprises a plurality of horizontally spaced upright hanger supporting units, each comprising a plurality of vertically spaced horizontally disposed hanger supporting elements. Each succeedingly

2

higher element is shorter than the element immediately below it, and cooperates with a corresponding element on the next adjacent support unit to furnish support for the ends of horizontally disposed garment hangers. The supporting units may be constructed in a variety of forms. Each may have an upright stanchion, to which the supporting elements are firmly attached, with its own floor-standing base, or two or three or more may be combined in a modular unit having the spaced upright stanchions to which the supporting elements are attached connected to a more or less conventional enlarged base structure. If desired, the supporting units may be cantilevered outwardly from a wall or suspended from above by wires or the like, with their supporting elements maintained in position by a central rigid member or a system of wires or guys, if necessary.

It is contemplated that many variations in the size, arrangement, proportion and construction of the several parts of the invention will occur to the skilled artisan, and these may be employed without departing from the scope or sacrificing any of the advantages thereof.

In the drawings:

FIGURE 1 is a perspective view of one preferred embodiment of the display, and storage rack of this invention;

FIGURE 2 is an enlarged fragmentary perspective view of the upper portions of two of the supporting units of the invention illustrated in FIGURE 1 showing the upper ends of their vertical stanchions, two cross-members, and two garment hangers;

FIGURE 3 is a fragmentary top plan view of a modified form of one of the cross-members illustrated in FIGURE 2, with a portion of one of the segments cut away to show its internal structure; and

FIGURE 4 is a fragmentary side elevation of the invention as illustrated in FIGURE 1, with a number of typical garments and their hangers shown in phantom as they might appear with the rack in use.

Referring to FIGURES 1 and 4, a base section 10 of generally rectangular configuration is formed of tubular members. Each side of base section 10 has upper and lower supporting bars 12 and 14, respectively, supported by side members 16. The structure is made rigid by provision of braces 18 intermediate each side member 16. As will be seen, the dimensions of the base section 10 and the horizontal spacing between adjacent pairs of bars 12 and bars 14 are dictated by the number of garments desired to be displayed and the length of the hangers used for supporting them.

Each side member 16 includes a foot 20 mounted on the portion of side member 16 which extends below the lower bars 14. The side members 16, upper bars 12, lower bars 14, and braces 18 may be connected permanently by welding, or demountably by any convenient releasable fastening means such as nuts and bolts. If releasable means are used, the stability of section 10 may be enhanced by connecting the various members, bars and braces in interfitting male and female relationships.

A plurality of hanger support units 22 are mounted on the upper bars 12. Each unit 22 comprises a mounting stanchion 28 and a plurality of cross-members 26. The cross-members 26 in each supporting unit 22 are all of a different length, with the longest member being located adjacent the base section 10 and each upwardly succeeding cross-member 26 being shorter than its lower neighbor. The cross-members 26 are fixed to stanchion 28 by welding or some other convenient means.

The spacing between adjacent pairs of units 22 is determined by the length of the hanger 24 which is to be used for the particular garments stored and displayed.

Base section 10 may be adapted to support any number of two or more units 22, but for illustrative purposes three are shown in the drawing.

It has been found that a support unit 22 formed by mounting five cross-members 26 varying in length from a maximum of about three feet to a minimum of about eight inches on a stanchion 28 about thirty inches in length is usually quite satisfactory for the efficient storage and attractive display of mens' trousers. However, the number of cross-members 26 and their particular lengths and the length of the mounting stanchions 28 are matters to be determined for each installation.

Each mounting stanchion 28 is connected to a respective upper bar 12 of the base section 10, directly in line with a brace 18. Each hanger support unit 22 is mounted so the cross-members 26 are generally parallel to the upper bars 12.

Each cross-member 26 is constructed of parallel segments 30 of a relatively inflexible material in rod or tubular form, the spacing between the segments 30 being such as to allow the insertion of the mounting stanchion 28 therebetween. To facilitate manufacturing, the segments 30 of each cross-member 26 are preferably connected by end sections 32, thereby forming a sturdy and continuous unit. The segments may, if desired, be of separate rod members and not connected except through mounting stanchion 28.

The cross-members 26 are preferably mounted at the mid-points of their respective segments 30 on their mounting stanchions 28, although such need not be the case. The tops of the corresponding cross-members 26 of all of the hanger units 22 lie substantially in a pair of planes extending on either side of each stanchion 28. Though preferably horizontal, these planes may be inclined upwardly or downwardly from the mounting stanchions 28 by the appropriate upward or downward inclining of the portions of segments 30 on one or both sides of stanchions 28.

Hangers 24 incorporate depending hook portions 34 at each of their ends to engage and derive support from cross-member segments 30 of corresponding pairs of cross-members 26 in adjacent supporting units 22. This configuration permits the hangers to be slid easily along their supporting cross-member segments 30 and to be removed and replaced with a minimum of effort.

The upper extremity of each mounting stanchion 28 is internally threaded as at 36 to receive and securely hold an advertising or display list holder, an ornament, or the like.

As is obvious from the foregoing, the display rack of this invention is of open construction, which allows for easy viewing of the garments while they are being stored. Because the cross-members 26 of each support unit 22 are arranged in upwardly diminishing lengths, a substantial portion of those garments hung on hangers 24 located farthest from a customer standing in front of the rack is clearly visible to him. If walking room is provided around base section 10, no garment will be more than eighteen inches from a customer of average height. If each of the tiers is used to support garments of a particular size, color or material, the customer approaching the rack will be able to observe examples of each without so much as touching them, and then remove the desired garment with its hanger from the rack for individual examination and fitting. To return the garment to its place is simply a matter of slipping its lower end between the cross-members 26 and lowering the hanger 24 until its hooked ends 34 engage the adjacent segments 30 of members 26.

FIGURE 3 illustrates an adjustable form of the cross-member 26 illustrated in FIGURE 2. The segments 30' are not solidly connected at their respective ends but left open. A frictional material 38, such as felt or the like, is fixed to the interior of each open end of each segment 30' as shown in FIGURE 3. End section 32' is

formed of smaller diameter tubular material than segment 30'. The difference in diameter is just sufficient to allow segment 32' to be securely fitted into the ends of segments 30', permitting longitudinal movement of end section 32', yet maintaining a fiction-tight connection at all times. In this manner the number of hangers which can be accommodated on each cross-member can be varied as required.

The versatility and a number of variations of the invention will be readily perceived from the foregoing description. For example, the number of garments on each of the cross-members 26 can be varied greatly, as can the height and depth of each tier of garments, by the proper dimensioning and locating of the cross-members 26 themselves. If desired, the garments may be displayed all on one cross-member 26 or on two or three tiers.

For greater flexibility in use, the supporting units 22 may be adapted to permit the positions of cross-members 26 on stanchions 28 to be adjusted upwardly or downwardly. This may be accomplished by any of a number of conventional means, such as constructing stanchions 28 in hollow tubular form, providing slots extending longitudinally in their outer sides, and attaching cross-members 26 to these sides by means of bolts having their heads within the stanchions 28 and their shanks passing through the slots and holes tapped through the cross-members 26 at their mid points and releasably secured by nuts threaded to receive them.

By effectively splitting cross-members 26 at the mid points of segments 30, and permitting the two ends of each to be adjustable rotatably about mounting means such as the bolt-and-slot mounting arrangement just described, the supporting means for hangers 24 can be adjusted upwardly or downwardly, as desired, on either 30 or both sides of supporting stanchions 28. With cross-members 26 thus articulated, it may be beneficial to provide hooks or stops at spaced intervals along the cross-members 26 to retain the hangers.

The base section 10 may be constructed to support any 40 number of support units 22, or several base sections 10 may be connected, either permanently or removeably, to form a large display and storage unit of any required shape.

Furthermore, the rack of the invention may be constructed without the unitary base section 10 shown in the drawings. For certain installations it may be advantageous to provide a plurality of upright stanchions 28 utilizing their own independent bases or a modified supporting structure.

As alternatives to a floor-resting support, the invention 50 may employ a system of ceiling supported suspension wires, or braces cantilevered from a wall, to support the hanger support units 22. The support units 22 themselves may be of rigid construction, as depicted in the drawings, or suspended from above by wires or the like.

In light of the foregoing, it will be understood that the 55 invention as shown and described is capable of considerable modification within the scope and meaning of the following claims.

60 What is claimed is:

1. A storage and display rack comprising:
at least two spaced hanger supporting units, each of said units including a plurality of vertically spaced horizontally disposed rigid cross-members comprising pairs of elongated parallel spaced rigid segments of varying lengths arranged in upwardly diminishing order of such lengths;
support means supporting said hanger supporting units and maintaining corresponding pairs of said cross-members in adjacent pairs of said units in substantially parallel coplanar relationship; and
hangers for garments comprising an elongated essentially rigid garment holding element adapted to extend between corresponding pairs of said cross-members.

bers, and having means at its extremities releasably engaging said cross-members for support.

2. The storage and display rack described in claim 1 in which said cross-members further comprise rigid elongated end sections extensibly engaging the ends of said pairs of segments, and thereby permitting the effective lengths of said cross-members to be selectively adjusted and preventing said hangers from slipping over said ends; and means retarding the movement of said end sections with respect to the ends of said pairs of segments. 10

3. The storage and display rack described in claim 1 wherein:

said support means comprise

a base section of substantially rectangular configuration comprising a plurality of parallel spaced substantially vertical rigid side members, substantially horizontal spaced rigid upper and lower members securely connected to said side members, and rigid brace members connecting said upper and lower members intermediate said side members, and

rigid upstanding stanchions securely connected to said base section at spaced intervals and maintained upright thereby; 25

said cross-members further comprise

rigid elongated end sections extensibly engaging the ends of said pairs of segments, thereby permitting the effective lengths of said cross-members to be selectively adjusted and preventing 30 said hangers from slipping over the ends of said segments; and

the segments comprising said cross-members are positioned on opposite sides thereof.

4. The storage and display rack described in claim 1 35 wherein:

said support means comprise

a base section of substantially rectangular configuration comprising a plurality of parallel spaced substantially vertical rigid side members, substantially horizontal spaced rigid upper and lower members securely connected to said side members, and rigid brace members connecting said upper and lower members intermediate said side members,

rigid upstanding stanchions securely connected to said base section at spaced intervals and maintained upright thereby; said cross-members further comprise

rigid elongated end sections extensibly engaging the ends of said pairs of segments, thereby permitting the effective lengths of said cross-members to be selectively adjusted and preventing said hangers from slipping over the ends of said segments; and

said cross-members are attached to said stanchions at vertically spaced intervals, with the segments comprising said cross-members positioned on opposite sides thereof.
